SHUTTLE

Emil E. Fuller, Woonsocket, R. I., assignor to
Shambow Shuttle Company, Woonsocket, R. I.,
a corporation of Rhode Island

Application March 18, 1933, Serial No. 661,533

4 Claims. (Cl. 139—217)

The present invention relates to shuttles and more particularly to self-threading shuttles for weft replenishing looms.

The object of the invention is to provide a shuttle having a tension device with provision for positive and accurate guiding of the thread into the eye after replenishment and for applying positive tension to the thread with minimum wear on the parts.

To this end, the invention comprises the shuttle hereinafter described and particularly defined in the claims.

In the accompanying drawing, Fig. 1 is a plan view of a portion of the preferred form of shuttle; Fig. 2 is a section on the line 2—2 of Fig. 1; Fig. 3 is a front elevation of a thread block; Fig. 4 is a section on line 4—4 of Fig. 3; and Fig. 5 is an end elevation on a somewhat enlarged scale of the block.

The illustrated embodiment of the invention comprises a shuttle 6 having a bobbin recess to receive a bobbin 8 of usual form. The shuttle is provided with a thread block 10 for guiding the thread from the bobbin into the eye 12 of the shuttle. The block is provided with a beak 14. The block also has a longitudinal unrestricted thread passage 18 which is aligned with the axis of the bobbin. At the rear end of the block there is provided an overhanging hook 20 to direct the thread into a guide slot 22 which leads into the thread passage.

A tension device comprising a pair of spring pressed metal pads 24 is located in the thread passage. The pads 24, as shown in Fig. 2, are of general L-shape, each having a longitudinally disposed portion 26 immediately below the thread passage and an upstanding vertical portion 28 at the front thereof. The faces of the pads are vertically disposed, the pads being mounted on a pin 30 extended across and immediately below the thread passage. The pin 30 is arranged at the rear end of the longitudinal portions of the pads. At the upper end of the upstanding portions, each pad is formed with a projection 32 which is received in a hardened metal cylindrical bushing 34 pressed in the body of the block, the purpose of the bushing being to resist wear on the block upon continual movement of the pads. As shown in Fig. 4, the top and bottom edges of the longitudinal portions 26 of the pads are beveled as are also the edges of the upstanding portions 28 in order to permit the thread to enter and leave the tension device without chafing. As shown in Fig. 5, the upper ends of the upstanding portions 28 are flared to provide a

V-shaped throat into which the thread is guided immediately after replenishment.

The pads are pressed toward each other by small coil springs 36 and 38. The spring 36 on the front side is received in a small bore of the block and the spring 38 on the rear side is received in an opposing bore. The bore in which the spring 36 is received does not extend through the block and the spring is therefore inserted from the thread passage. The bore into which the spring 38 is received extends through the rear side wall of the block. A feature of the invention consists of means whereby the tension on the pads may be adjusted. In order to avoid the use of adjusting screws, which would have to be placed on the rear wall of the shuttle with consequent danger of damage to the reed, the invention contemplates an arrangement permitting removal and exchange of the spring 38. The spring 38 is held in place by a thin sheet metal retaining member 39 having a side plate 40 bearing against the spring. The member also has a bottom plate 42 provided with an elongated opening 44. The positioning stud 46 of the block is undercut to receive the bottom plate 42. The spring retaining member is further held in position by a hook-like projection 48 on the front end which is received in a slot in the rear side wall of the block. Normally the spring retaining member is held by engagement with the inside wall of the shuttle in the position shown in Fig. 5. When it is desired to change the spring tension, the block is removed from the shuttle and the retaining member is swung to the position indicated in dot-and-dash lines in Fig. 4 to one side. The bottom plate 35 may then be disengaged from the undercut stud 46 and removed from the block, permitting insertion of a spring of different strength in place of the spring 38. It is unnecessary to change both springs since sufficient variation in tension may be obtained by changing the rear spring only.

In operation, the thread unwinding from the bobbin on the first pick after replenishment enters the thread passage through the guide slot 22 and after passing under the beak 14 it enters between the flaring vertical portions 28 of the tension pads. On the second pick, the thread passes down into the eye of the shuttle. Thereafter, the thread rides over a pin 56 disposed across the thread passage and also over the pin 30 which supports the tension pads. In passing between the pin 56 and the eye of the shuttle, the thread is engaged by the opposed pads and is held under a light but positive tension. Owing to the beveled construc-

tion of the pads, the thread enters and leaves the pads without chafing or danger of breaking.

It will be noted that the longitudinal portions of the pad which provide the tensioning effect on the thread are located in close proximity to the eye of the shuttle. This feature is desirable in that it holds the thread under positive control. It has been found that when a tension device is placed back from the eye, there is a tendency for the thread to snarl internally of the block when the shuttle is suddenly stopped by entering a box at the end of the pick, particularly if the thread is of silk or rayon. With the positive control immediately adjacent to the eye, as afforded by the present invention, there is no possibility for such action to occur. Furthermore, it will be seen that the L-shaped construction of the pads affords positive guiding of the thread into the longitudinal spring-pressed portion. The upstanding parts 15 of the pads extend well above the center of the thread passage so that the thread is positively engaged thereby on the first pick after replenishment. On the second pick, the thread is easily guided between plates into the eye of the shuttle.

20 The L-shape of the tension further provides for distribution of wear, since the thread continually changes its position between the pads as the shuttle is picked first in one direction and then the other.

25 Having thus described the invention, what is claimed is:

1. A shuttle having an eye, a block having a longitudinal thread passage, a tension device including longitudinally disposed pads arranged adjacent to the eye and below the thread passage.

and from which the thread leads directly to the eye, each pad having an upstanding thread guiding portion at the front end of the thread passage.

2. A shuttle having an eye, a block having a longitudinal thread passage, a tension device comprising a pair of pads having opposed vertical faces, each pad being L-shaped and having a longitudinally disposed portion below the thread passage and immediately adjacent to the eye and from which the thread leads directly to the eye, 10 each pad also having an upstanding portion at the front end of the thread passage to engage the thread during threading of the shuttle, and means for yieldingly pressing the pads together.

3. A shuttle having an eye, a block having a 15 longitudinal thread passage, a tension device comprising a pair of opposed L-shaped pads, each pad having a longitudinally disposed portion from which the thread leads directly to the eye and an upstanding vertical portion with a flared upper 20 end at the front end of the longitudinally disposed portion, a pin for supporting the rear part of the longitudinal portions of the pads, and spring means for pressing the pads together.

4. A shuttle having an eye, a block having a 25 bottom stud, a tension device comprising opposed pads, a coil spring for yieldingly pressing the pads together, and a retaining member for the spring including a side plate and a bottom plate, the bottom plate having an elongated opening to fit 30 over the stud, the stud being undercut to lock the retaining member when the side plate is pressed against the wall of the block.
